(57) **CLAIM**

The ornamental design for a lamp assembly, as shown and described.

DESCRIPTION

FIG. 1 is a perspective view of a lamp assembly showing my new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

All the support structures, except the horizontal mounting bars, are shown in broken lines for the purpose of illustrating environmental structure that forms no part of the claimed design. The broken away symbols in the drawings indicate that the appearance of any portion of the article between the break lines forms no part of the claimed design.
